(57) **CLAIM**

The ornamental design for a tubing clip as shown and described.

DESCRIPTION

FIG. 1 is a top font-left perspective view of a tubing clip; FIG. 2 is a top plan view thereof; FIG. 3 is a bottom plan view thereof; FIG. 4 is a rear elevation view thereof; FIG. 5 is a front elevation view thereof; FIG. 6 is a left side elevation view thereof; FIG. 7 is a right side elevation view thereof; FIG. 8 is a right front perspective view thereof; FIG. 9 is a left front perspective view thereof; FIG. 10 is a right rear perspective view thereof; FIG. 11 is a left bottom perspective view thereof; and, FIG. 12 is a cross-sectional view of the tubing clip of FIG. 1, taken in the direction of line 12-12 identified in FIG. 7. The equal-length broken lines in the drawings depict portions of the tubing clip that form no part of the claimed design. The dash-dot-dot-dash lines depict the bounds of the claim and form no part of the claimed design. All broken lines form no part of the claim.
